J. H. BOOM.
TRAIN STOP SYSTEM.
APPLICATION FILED JAN. 10, 1912.

Patented Feb. 18, 1913.

UNITED STATES PATENT OFFICE

JOHN H. BOOM, OF NEW YORK, N. Y., ASSIGNOR OF TWO-FIFTHS TO FRANK BACH AND NINE ONE-HUNDREDTHS TO KARL EMIL WILHELM BICHELS, OF NEW YORK, N. Y.

TRAIN-STOP SYSTEM.

1,053,899.

Specification of Letters Patent. Patented Feb. 18, 1913.

Application filed January 10, 1912. Serial No. 670,410.

To all whom it may concern:

Be it known that I, JOHN H. Boom, a citizen of the United States of America, residing at New York, in the county of New York and State of New York, have invented certain new and useful Improvements in Train-Stop Systems, of which the following is a specification.

The present invention has for its object 10 to provide a train stop system of the automatic type, whereby vehicles running on a single track or on intersecting tracks will be prevented from colliding when approaching one another within a given distance.

15 In my new system I make use of two electric conductors which extend preferably in the middle of the track and which are divided in equal sections of a mile or more, a section of one conductor in one block being 20 conductively connected to a section of the opposite conductor in the next block. Each train is equipped with a battery or other electric source, a motor operatively connected to the power controller and brakes, 25 a commutator, two relays, a series of contact shoes, of which two are adapted to slide over the said electric conductors and the others are adapted when the train is about 30 to enter the block next to the crossing to come into contact with short conductors conductively connected to the track, and electric connections between the electric source and the different parts named to bring about the effect to be presently described.

35 My invention is diagrammatically illustrated in the accompanying drawing, which forms a part of this specification and in which similar reference letters denote corresponding parts, Figure 1 representing a single track system and Fig. 2 showing the connection of the motor to the power controller and brakes.

With reference to Figs. 1 and 2, let A 40 and B denote the tracks, crossing one another. Let A', A² denote two electric conductors for the track A and B', B² denote two electric conductors for the track B. For the sake of clearness, let us call the electric conductors A' and B' the motor lines, and A², B² the battery lines. On each track a section of the battery line in one block is conductively connected in a diagonal line to a section of the opposite motor line in

the preceding block and at the crossings the 55 intersecting sections of the battery line on the track A and the motor line on the track B and vice versa are conductively connected. Let T', T² and T³ denote trains or cars, of which trains T', T² are on the track 60 A and T³ is on track B and let the arrows indicate the direction of travel. Since each train is equipped with the same parts, I shall for brevity's sake denote the same parts by corresponding reference letters and numerals, bearing different exponents, thus the parts of train T' bear the exponent 1, those of train T² bear the exponent 2 and those of train T³ the exponent 3. I shall now describe only the parts of train T', it 65 being understood that the same description also applies to the other two trains shown, with the exception that references with the corresponding exponents are to be substituted for those of train T'. 75

a' denotes an electric source, b' a motor which may be operatively connected to the power controller and brakes of the train in any suitable manner.

c' denotes a commutator for changing the 80 direction of the electric circuit in accordance with the direction of travel of the train. Such commutator is necessary, for without it, when the direction of travel of the train is reversed it would operate instead of rearwardly, as intended, on a train ahead, stopping the latter and being thus permitted to run into the said train ahead. By the commutator, however, all the electric connections between the different instruments can be so adjusted that no matter in which direction the train travels it will always operate on a rear train running on the same track when coming within a 85 given distance therefrom. 90

x', y' denote a pair of electromagnets arranged opposite one another and d' is the armature fulcrumed at a point between the two electromagnets and forming with the latter and a contact point e' a relay. j' denotes an electromagnet which with the contact points k', l' forms another relay. 95

E', D' are contact shoes adapted to travel along the sectional conductors of the track.

f', g', h' and i' are contact shoes which 100 normally have no function, except, as will be seen, when the train enters or is about to leave the block nearest to the crossing and

when said shoes come into contact with short rails m^a , n^a , o^a of the track A (or correspondingly m^b , n^b , o^b on track B). The electric connections are indicated by reference numerals.

- 5 The commutator comprises an adjustable arm having insulated sections and contact points p' , q' , r' , s' , t' , u' , v' , and w' arranged in pairs, so that the arm when in 10 contact with the latter will establish electric connections only between the contact pieces forming a pair, whereas the contact pieces of two different pairs are insulated from one another.
- 10 15 Let us now consider two trains approaching each other within a given distance on the track A' . T^2 being the overtaking train, it is desired that it be stopped by the forward train T' .
- 15 20 The current flows from the + pole of the battery a' along wire l' to the contact point q' of the commutator, thence passing over to contact point p' and thence to the contact shoe D' resting on a section of the 25 conductor A^2 which I call the battery line. The train T^2 having approached T' so far that its contact shoes E^2 , D^2 contact with the sections in the preceding block of the conductors A' , A^2 the current is allowed to 30 pass over to the preceding section of the opposite motor line A' and to flow along that section to the contact shoe E^2 . From here it flows along wire 11^2 to contact point s^2 , passing over to contact point r^2 , thence 35 along wires 9^2 , 8^2 to the armature d^2 of relays x^2 , y^2 and being in contact with point e^2 , it passes to the latter and along wire 12^2 , through the motor b^2 , along wire 40 10^2 to the track, along the latter to the 45 wheels of train T' and through wire $13'$ to the - pole of the battery a' . The motor b^2 of train T^2 by the circuit of the battery a' of train T' will be set in operation and will perform the desired function in operating the brakes and power controller of 50 said train T^2 in any suitable manner. If the train T^2 is farther from train T' than the given distance, that is to say, its contact shoes or trolleys E^2 , D^2 are not on the sections next preceding those on which the contact pieces E' , D' of train T' rest, then there is no electric connection between the contact shoe D' of train T' and the contact shoe E^2 of train T^2 and the motor of the 55 latter will not be operated. On the other hand, no matter where the train T^2 stands relative to train T' the latter's motor will not be affected by the battery of the former.
- 55 60 We will now consider the operation of the trains T' , T^2 on the cross tracks A, B. At points near the beginning of the sections of the conductors next to the crossing I provide on the tracks A, B short rails m^a , n^a and m^b , n^b respectively. Then when 65 the train T^2 arrives first at the given distance from the crossing its battery will be ready to operate the motor of train T' arriving later at the block next to the crossing on track A, the current of the battery a^2 flowing from the + pole of the latter along 70 wire l^2 , contacts q^3 , p^3 , wire 2^3 , contact shoe D^3 , conductor B^2 , conductor A' , contact shoe E' , wire $11'$, contact points s' , r' , wires $9'$, $8'$, armature d' , contact e' , line $12'$, motor b' , wire $10'$, to track A, thence back to 75 track B, wire 13^3 to - pole of battery a^3 . The motor of train T' will be operated. If train T^3 is first to enter on the block nearest the crossing, it will in the aforesaid manner be allowed to operate train T' , if 80 the latter has advanced so far that its contact shoe E' entered on the section of the block nearest the crossing. Simultaneously with the contact shoes E' , D' entering on the forward section nearest the crossing, the 85 contact shoe g' is adapted to come into contact with the short rail m^a . In consequence thereof, and because of the train T^3 being first on the block nearest the crossing, a second battery circuit of train T^3 will be 90 closed, the current flowing from the + pole of said battery along wire l^3 to contacts q^3 , p^3 , wire 2^3 , contact shoe D^3 , conductors B^2 , A' to contact shoe E' , wire $11'$, contact points s' , r' , wire $9'$, $8'$, relay j' , contact shoe g' , rail m^a to track A, thence to track B back to the - pole of battery b^3 along wire 95 13^3 . In consequence thereof, the armature of relay j' will be attracted and contact between point k' , l' broken. The consequence 100 of this will be that train T' could not render itself immune from the influence of the train T^3 , e. g. it could not prevent the battery a^3 of train T^3 operating its motor b' . On the other hand, the train T^3 , in which 105 the connection of contacts k' , l' is not broken, renders itself immune as soon as its contact shoe f^3 arrives at the short rail n^b . For at this point a circuit of its own battery passing through its relay x^3 is closed, 110 the current flowing from the + pole of the battery a^3 along wires 1^3 , 3^3 , 4^3 , to contacts w^3 , v^3 , thence through wire 5^3 to relay x^3 , thence to contacts l^3 , k^3 , thence along wire 115 7^3 , to contact shoe f^3 , thence through rail n^b to track B, thence through wire 13^3 to the - pole of battery a^3 . By reason of this circuit, the armature d^3 is attracted and becomes disconnected from the contact point e^3 . Now, if the train T' owing to its inertia 120 still advances, so that its contact shoe D' enters on the forward section of the battery line, it can have no effect on the train T^3 because the circuit of battery a' remains open and train T^3 may proceed, while train 125 T' remains stationary until the former has passed the danger point. At another point of the tracks A, B there are short rails o^a , o^b respectively which are conductively connected to the tracks and which serve to restore 130

the armatures d' , d^3 to their normal position. When the train T^3 (referring to above example) reaches the rail o^b , and its contact shoe i^3 gets into contact with it, then 5 its own battery circuit will be again closed, the current flowing from + pole along wires 1^3 , 3^3 , contacts u^3 , t^3 , wire 15^3 through relay y^3 , wire 16^3 , contact shoe i^3 , rail o^b , track B, wheels of the train T^3 to the - pole of the 10 battery a^3 . In consequence thereof, the armature d^3 will be attracted in the opposite direction and make again contact with point e^3 . When the train is turned around to move in the opposite direction, the same will 15 take place by adjusting the arm of the commutator c' (c^2 or c^3) to contact with the opposite contact points not marked by reference letters.

Fig. 2 shows by way of example a mode 20 of operatively connecting the motor of a train with the corresponding power controller P and air brake K. The controller lever L is suitably connected to a piston rod R of a piston R' working in a stationary 25 air cylinder C. The piston R' is operated from the motor b by a set of gears G and a rack M formed on the extension of the rod R, so that when the motor b is set in motion by the battery circuit of another train, it 30 will positively displace the lever L of the power controller P to shut off the power. The air brake pipe may be provided with a number of valves V' , V^2 , V^3 which by the 35 displacement of the lever L will be alternately opened and closed to gradually apply the brakes. The return of the controller lever L into the starting position may be obtained by a spring S. This return movement of the lever will be counteracted by 40 the air previously drawn into the cylinder through the suction valve H.

What I claim and desire to secure by Letters Patent is:

1. In a train stop system, the combination 45 with a track, of two sectional electric conductors along the track, dividing the latter into uniform blocks and of which a section in one block of one conductor is conductively connected to a section in the next block of the other conductor, a moving vehicle having an electric source of which one pole is connected to the track and the other to one of said sectional conductors, a motor, a circuit breaker, means for operating the latter, one pole of said motor being conductively connected to the track and the other pole thereof to said second conductor, said connection leading through said circuit breaker, means conductively connected to the track, means on the vehicle 50 adapted to control said first named means and to make contact with the second named means, and an electric connection between said electric source and said third named means, so that when contact is made between 55 said second and third means the said circuit

breaker will be actuated to break the connection between said motor and the said second conductor.

2. In a train stop system, the combination with a track, of two sectional electric conductors along the track dividing the latter into uniform blocks and of which a section in one block of one conductor is conductively connected to a section in the next block of the other conductor, a moving vehicle having an electric source of which one pole is connected to the track and the other to the one of said sectional conductors, a motor, a circuit breaker, means for operating the latter, one pole of said motor being conductively connected to the track and the other pole to the said other conductor, said connection leading through said circuit breaker, a contact rail adjacent and conductively connected to the track, a contact point on the vehicle adapted to make contact with said rail, an electric connection between said electric source and the said contact point, so arranged that when the circuit is closed by the contact of said contact point and rail, 90 said circuit will control said first named means, and a second circuit breaker interposed between said first named means and said contact point, so that when the connection between said first named means and said contact point is broken by said second circuit breaker the contact made between said contact point and rail will be ineffective and the breaking of the connection between the motor and the second conductor is prevented. 95

3. In a train stop system, the combination with a track, of two sectional electric conductors along the track, dividing the latter into uniform blocks and of which a section in one block of one conductor is conductively connected to a section in the next block of the other conductor, a moving vehicle having an electric source of which one pole is connected to the track and the other to one of said sectional conductors, a motor, a circuit breaker, electrical means for operating the latter, one pole of the motor being conductively connected to the track and the other pole thereof to said second conductor, said connection leading through said circuit breaker, contact rails conductively connected to the track, two contact points on the vehicle adapted to successively make contact with the respective contact rails, an electric connection between the electric source, said electric means and one contact point, a second circuit breaker interposed between said electric means and said last named contact point, electrical means for operating said second circuit breaker, an electric connection leading from the other contact point through said second circuit breaker and operating means to said second conductor, so that when contact is made between the last named con- 125

tact point and its respective contact rail, while the second conductor is energized by a circuit flowing through it and the track, the said second circuit breaker will be caused to break the connection between the first named means and the first named contact point.

4. In a train stop system, the combination with a track, of two sectional electric conductors along the track, dividing the latter into uniform blocks and of which a section in one block of one conductor is conductively connected to a section in the next block of the other conductor, a moving vehicle having an electric source of which one pole is connected to the track and the other to one of said sectional conductors, a motor, a circuit breaker, separate electrical means for opening and closing the latter, one pole of the motor being conductively connected to the track and the other pole thereof to the said second conductor, said connection leading through said circuit breaker, two contact rails conductively connected to and arranged at different places along the track, two contact points on the vehicle adapted to successively make contact with the respective contact rails, electric connections between said electric source and said two contact points, said connections leading through said electrical opening and closing means respectively, whereby when one of said contact points makes contact with its respective rail, the circuit breaker will be opened and when the other contact point makes contact with its contact rail the circuit breaker will be closed.

5. In a train stop system, the combination with a track, of two sectional electric conductors along the track dividing the latter into uniform blocks and of which a section in one block of one conductor is conductively connected to a section in the next block of the other conductor, a moving vehicle having an electric source of which one pole is connected to the track and the other to one

of said sectional conductors, a motor, a circuit breaker, separate electrical means for opening and closing the latter, one pole of said motor being conductively connected to the track and the other pole thereof to the said other conductor, said connection leading through said circuit breaker, three contact points carried by said vehicle, three contact rails therefor conductively connected to the track and of which two are arranged adjacent to each other and one at a distance from the said two contact points, the said contact points being adapted to successively come into contact with their respective rails, an electric connection between said electric source and one of said adjacent contact points, an electric connection between the electric source and the said third contact point, said electric connections leading through aforesaid electrical opening and closing means respectively, a second circuit breaker interposed between the aforesaid one of the two adjacent contact points and the said electric means for opening the first named circuit breaker, electrical means for operating said second circuit breaker, an electric connection leading from the other of the two adjacent contact points and through said second circuit breaker operating means to said second conductor so that when contact is made between the last named contact point and its respective contact rail while the second conductor is energized by a circuit flowing through it and the track the said second circuit breaker will be caused to break the connection between the opening means of the first named circuit breaker and the first of the two adjacent contact points.

In testimony whereof I affix my signature in presence of two witnesses.
